ATTORNEY

UNITED STATES PATENT OFFICE.

CHARLES C. F. NIESCHANG, OF FORT WAYNE, INDIANA.

SIGNAL.

1,019,827.

Specification of Letters Patent. Patented Mar. 12, 1912.

Application filed September 1, 1911. Serial No. 647,174.

To all whom it may concern:

Be it known that I, CHARLES C. F. NIESCHANG, a citizen of the United States of America, and resident of Fort Wayne, in 5 the county of Allen and State of Indiana, have invented certain new and useful Improvements in Signals, of which the following is a specification.

This invention relates to improvements in 10 signals, and the object thereof is the provision of a device to aid venders, of such merchandise as ice, to determine the quantity of ice or other merchandise desired by the customer without making inquiry.

15 The object of this invention is accomplished by the construction illustrated in the accompanying drawings in which—

Figure 1 is a front elevation of the device, 20 and Fig. 2 is a side view of the upper portion of Fig. 1.

Similar characters of reference indicate 25 corresponding parts in both views, and referring now to the same: A is a disk having a lower extension B to which is attached a supporting standard C. The disk is circular except for the extension B which extends beyond the radius of its upper portion. At the center of the disk is attached a signal plate D by means of a pivot E upon which 30 the plate D is adapted to be turned. One end of the plate D projects beyond the marginal edge of the circular portion of the disk, the projecting portion being so formed as to be covered by the projection B of the 35 disk when the projecting portion of the plate D is moved to its lowermost position. To the plate D is attached a secondary signal plate F by means of a pivot G upon which it is adapted to be turned. One end 40 of the plate F is adapted to project beyond the outermost end of the plate D when in its extended position. The opposite end of plate F is shorter and narrower than the former end and when it is turned outward 45 the entire plate becomes obscured from view, from the front of the device, by the plate D and disk A.

Horizontally across the center of the disk A is painted a stripe H in bright color, such 50 as yellow as indicated at H, and the upper and lower portions of the disk adjoining the stripe are painted, or otherwise finished in a dark color, such as black, as indicated at I and J. Thus, the stripe is made to appear 55 in sharp contrast with the remaining surface of the disk. The projecting portion of

the signal plate D is finished to contrast sharply in color with both the stripe on the disk and the coloring on its remaining surface. Such a color as red answering the 60 purpose. The secondary signal plate F also is finished with a color to contrast with that of the plate D. Such a color as yellow answering the purpose.

Upon the disk A, at a point to one side of 65 its vertical center and beneath the stripe H is placed an indicating member, such as 25; upon the same side of the disk, but above the stripe is placed another indicating number of greater denomination than the former 70 number, such as 50; upon the opposite side of the disk, above the stripe is placed an indicating number exceeding either of the former numbers; and beneath the stripe upon the latter side of the disk is placed another 75 indicating number exceeding in denomination the last named.

In using the device it is the intention that 80 customers will be provided, each with one of the devices for use in the following manner: The device is to be set up upon its standard in a convenient place where it may readily be seen by the vendor from his vehicle, and the plates so turned upon their pivots as to indicate the amount of merchandise 85 desired. For instance, should the customer desire 25 lbs. of ice the plate F would then be turned so as not to project beyond the plate D, and the plate D is turned so as to project from that portion of 90 the disk upon which the indicating number 25 is placed. The vendor will thereupon notice the relation of the projecting end of the plate D to the stripe H, and though he may be unable to distinguish the indicating number, he will be enabled to ascertain its 95 denomination through his previous knowledge of the arrangement of the device. Should a greater amount of merchandise be desired, the plate D is turned to such positions as 100 will indicate the corresponding amount wanted. Should a still greater amount of merchandise be desired than the indicating numbers upon the disk signify, the secondary signal plate F is turned so as to 105 project beyond the plate D, thus indicating to the vendor that an additional amount is desired to that indicated by the position of the plate D. For instance, such additional amount may be, by mutual understanding 110 between the customer and the vendor, to be 100 lbs. When no merchandise is desired

by the customer, the plates are turned upon their pivots so as to become completely obscured from view. With such a device in use, the time ordinarily consumed in trafficking such merchandise is economized materially. It avoids making inquiry of the consumer as to the amount of merchandise desired and, by adjusting the device at a convenient time so as to indicate the amount 10 of merchandise desired, the customer avoids responding to inquiries of the vendor.

What I claim as new and desire to secure by Letters Patent is:—

1. In a device of the class described, a circular disk having upon its face a diametral stripe, and having an extended portion; a signal plate pivotally supported at the center of the disk and with one of its ends projecting beyond the perimeter thereof; and a

secondary signal plate pivoted to the former plate on the rear side thereof, one end of which projects beyond the outer end of the former plate when in extended position. 20

2. In a device of the class described, a disk having a suitable means of support; a signal plate pivoted to the disk, one end of which extends beyond the perimeter thereof; and a secondary signal plate attached to the former signal plate upon the back thereof and adapted to be shifted so that one portion of its face will become projected beyond the outer end of the former signal-plate. 25 30

In testimony whereof I affix my signature in presence of two witnesses.

CHARLES C. F. NIESCHANG.
